US00D928075S

(12) **United States Design Patent** (10) **Patent No.:** **US D928,075 S**
Wu (45) **Date of Patent:** **** Aug. 17, 2021**

(54) **INTERNAL PROTECTIVE COVER FOR AUTOMOBILE ROOF**

(71) Applicant: **Tianjin ICONIQ New Energy Vehicle Co., Ltd.**, Tianjin (CN)

(72) Inventor: **Nan Wu**, Tianjin (CN)

(73) Assignee: **Tianjin ICONIQ New Energy Vehicle Co., Ltd.**, Tianjin (CN)

(**) Term: **15 Years**

(21) Appl. No.: **29/712,059**

(22) Filed: **Nov. 5, 2019**

(30) **Foreign Application Priority Data**

May 5, 2019 (CN) 201930213225.9

(51) **LOC (13) Cl.** **12-16**

(52) **U.S. Cl.**

USPC **D12/401**

(57) **CLAIM**

The ornamental design for an internal protective cover for automobile roof, as shown and described.

DESCRIPTION

FIG. 1 is a front view of the design for an internal protective cover for automobile roof;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

1 Claim, 7 Drawing Sheets
